UNITED STATES PATENT OFFICE.

ERNEST E. BUSER, OF PHILADELPHIA, PENNSYLVANIA.

HAMMER AND DAMPER SPRINGS FOR PIANO ACTIONS.

Application filed June 9, 1922. Serial No. 566,928.

To all whom it may concern:

Be it known that I, ERNEST E. BUSER, a citizen of the United States, residing at Philadelphia, in the county of Philadelphia and State of Pennsylvania, have invented certain new and useful Improvements in Hammer and Damper Springs for Piano Actions, of which the following is a specification.

10 This invention relates to piano actions and more specially to hammer and damper springs.

The object of the invention is to provide springs for the hammers and dampers of piano actions which can be readily attached and which do not require dismantling of the parts.

In the drawings,—

20 Figure 1 is a fragmentary vertical sectional view of the upper portion of a piano with the improvement applied to the piano action,

25 Figure 2 is an enlarged front elevation of a portion of the damper rail with the device applied, and

Figure 3 is a vertical sectional view taken on the line 3—3 of Figure 2.

In piano actions, the springs which hold the dampers against and the hammers away from the strings, are permanently affixed to the hammer and damper rails, respectively. When these springs break, it is necessary to dismount and replace the damper and its flange in order to renew the damper spring, and to remove portions of the broken springs before replacement can be made. Thus, replacements are accomplished with much difficulty.

It is therefore the purpose of the present invention to provide hammer and damper springs and attaching means therefor adapted to be applied to the damper rail to hold the dampers against and the hammers away from the strings and to obviate the necessity of detaching the parts of the piano action in replacing broken springs.

In illustrating the application of the invention, a piano 10 is shown and it is understood that this term comprehends automatic player pianos. The keyboard is designated at 11 on which the keys 12 are pivoted to actuate the lifter bar 13. 14 is the whip pen pivoted to the hammer rail 15 and bearing the arm 16 engaging the lower arm of the damper bar 17 pivoted to the flange 18

secured by a screw or other fastening means as designated at 19 to the top edge of the hammer rail 15. The damper bar 17 has on its upper end a shank 20 on which the damper 21 is mounted and adapted to be normally held against the strings, one of which is designated at 22.

The hammer 23 is pivoted to a flange 24 also attached to the hammer rail 15, the hammer having an enlargement 25 engaged by the usual spring-pressed striker 26 and co-operating with the usual spring stop 27, tie 28 and wire 29. The damper rail is designated at 30 and the hammer check at 31.

The damper bar 17 is usually engaged at 70 its upper end by a spring carried by the flange 18 to hold the damper 21 against the string and the hammer is held away from the string by a spring secured to a rabbeted lower portion of the damper rail 30. In accordance with the present invention, there is provided a substantially inverted U-shaped clip 32 preferably of spring metal to fit over and grip the damper rail 30. The intermediate or bight portion 33 of the clip is 75 disposed at the top of the damper rail and the leg portion 34 is longer than the leg portion 35, the former engaging the felt 36 at the back and the latter engaging the front of the damper rail and terminating at the 80 rabbeted portion 37.

Secured to the leg portion 34 near the lower end thereof as indicated at 38 is a spring strip 39 which is disposed against the leg portion for a short distance, then 90 extends upwardly and rearwardly and terminates in a vertical portion 40 adapted to engage the damper at the shank portion 20 of the bar 17 beneath the head of the damper 21. This spring holds the damper toward the string 22.

Secured to the leg portion 35 is a forwardly and upwardly curved spring 41 preferably of resilient wire having coils 42 and a hooked portion 43 engaging vertically spaced apertures 44 in the leg portion 35 as means of attaching or mounting the spring. The coils 42 are disposed against the front of the leg portion 35 and exert their tension to hold the spring forwardly and upwardly. 105 The free end of the spring is curved downwardly and rearwardly in a reverse direction as indicated at 45 so as to fit the felt covered vertical recess or groove in the enlargement 25 of the hammer rail and hold 110

the hammer away from the string 22. The device is equally applicable to new constructions or replacements.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by

15 Letters Patent is:—

1. The combination with a hammer rail supporting a hammer and a damper, and a damper rail, of removable means on the damper rail, and springs secured to the removable means for engaging the hammer and damper.

2. The combination with a hammer rail supporting a hammer and a damper, and a damper rail, of a clip on the damper rail, 25 and springs secured to the clip for engaging the hammer and damper.

3. The combination with a hammer rail supporting a hammer and a damper, and a damper rail, of a U-shaped spring clip on 30 the damper rail; a spring secured to one leg of the clip for engaging the hammer, and a spring secured to the other leg of the clip for engaging the damper.

4. The combination with a hammer rail supporting a hammer and a damper, and a 35 damper rail, of a U-shaped spring clip on the damper rail; a downwardly extending spring secured to one leg of the clip for engaging the hammer, and an upwardly extending spring secured to the other leg 40 of the clip for engaging the damper.

5. A spring clip adapted for use with a hammer and damper of a piano action; a spring secured to one end of the clip for engaging the hammer, and a spring secured 45 to the other end for engaging the damper.

6. A spring clip of U-shape; a downwardly extending spring secured to one leg of the clip for engaging the hammer, and an upwardly extending spring secured to the 50 other leg of the clip for engaging the damper.

7. A spring clip of U-shape; a downwardly extending wire spring secured to one leg of the clip for engaging the hammer, and an 55 upwardly extending flat strip spring secured to the other leg of the clip for engaging the damper.

In testimony whereof I have signed my name to this specification in the presence 60 of two subscribing witnesses.

ERNEST E. BUSER.
